UNITED STATES PATENT OFFICE.

MATTHEW J. FLANNERY, OF MATTESON, ILLINOIS.

MEANS FOR OPENING DOORS.

1,171,032.

Specification of Letters Patent.

Patented Feb. 8, 1916.

Application filed July 26, 1915. Serial No. 41,891.

To all whom it may concern:

Be it known that I, MATTHEW J. FLANNERY, a citizen of the United States, residing at Matteson, in the county of Cook and State of Illinois, have invented a new and useful Means for Opening Doors, of which the following is a specification.

My invention relates to improvements in means, in connection with sliding doors, for forcing the doors to initial open condition when, under the conditions presented, the doors in being closed are jammed tight, or otherwise present undue resistance to opening, as for example, in the case of freight car doors.

My object, generally stated, is to provide for use on freight cars or other structures wherein the doors are apt to require the application of relatively great force to initially open them, improved means for initially forcing the door open.

Referring to the accompanying drawings—Figure 1 is a broken face view of a freight car showing a part of the door-jamb and the door thereof equipped with my improved door shifting means, shown in combination with fastening means, the door being shown in closed position and fastened in place by said means. Fig. 2 is an enlarged section taken at the line 2 on Fig. 1 and viewed in the direction of the arrow. Fig. 3 is a similar view, showing the catch of the fastening means released from the keeper. Fig. 4 is a section taken at the line 4 on Fig. 1 and viewed in the direction of the arrow; and Fig. 5, a section taken at the line 5 on Fig. 3 and viewed in the direction of the arrow.

According to the preferred illustrated embodiment of my invention the door-opening means comprises a bar 23 on the door 12, this bar having a bearing in an apertured lug 24 on the casing 14 hereinafter described and guidedly confined at another point between the edge of the casing and a lug 25 thereon. The left-hand end of the bar 23 is adapted to engage the wall of the door-opening in which the door 12 operates and to provide for this manner of operation, the bar 23 is by preference provided with a rearwardly extending flange or lip 29 which is located in a recess 30 in an edge of the door and opposes the wall of the door-opening as shown. Any suitable means for actuating the bar 23 to force it against the

wall of the door-opening to force the door open, may be provided, those illustrated and which I prefer to employ, comprising a lever 31 which is journaled on a pin 32 secured to, and extending laterally from, the door 12, the lever being connected at its upper end with the right-hand end of the bar 23 through the medium of a pin 33 secured to the lever 31 and operating in a slot 34 in the bar 23.

In the preferred embodiment illustrated my improved door-opening means are provided in combination with locking means for the door and so arranged that upon a single act of swinging the lever 31 to the right in Fig. 1, the lock is first released and thereafter the door pushed open. In the arrangement shown a keeper, represented at 6 is provided, this keeper being shaped as shown to conform to one of the side rails 7 of the door-jamb of the car, the keeper being provided with apertures 8 to receive bolts 9 for rigidly securing the keeper in position. The keeper 6 is provided with a shoul-dered portion 10 which extends inwardly beyond the side rails 7 and is united with a plate-section 11, which extends in an upwardly inclined direction rearwardly from the shoulder 10, this plate being provided with two apertures 13 and 13^a. The fastening means also involves a catch-device which is carried by the door 12, this device being formed of a base member 14 and the catch proper 15. The member 14 is secured to the face of the door, as by screws 16, and is provided with a cross-piece 17 engaged by the catch proper 15 under the action of the spring 18 located at one side of the cross-piece 17. The end of the catch 15 opposite to that engaged by the spring 18 is pro-vided with a shoulder 19 from which an upwardly inclined plate 20 extends. The parts described are so proportioned that when the door is closed, as represented, the shoulder 19 will interlock with the shoulder 10 of the keeper, and the plate 20 will lie against the plate 11, in which position apertures 21 and 22 in the plate 20 will register with the apertures 13 and 13^a, permitting the fastening means to be sealed, if desired. It being understood from the foregoing that by reason of the construction of the parts as shown and described, the catch 15 will automatically interlockingly engage with the keeper 10 upon the act of

closing the door 12 and preventing opening of the door until the shoulder 19 has been released from the keeper.

In the construction illustrated the catch 15 is operated to release it from the keeper by the movement of the bar 23 to the left in Fig. 1, the parts being so arranged, that when the bar 23 is actuated the catch will be first released from the keeper and further movement of said member will force the then unlocked door to initially open condition. In the construction illustrated this is accomplished by means of a cam 26 on the bar 23 adapted to ride against a cam-surface 27 provided on a lug 28 extending laterally from, and secured to, the catch 15, these cam-surfaces moving against each other to swing the catch 15 away from the keeper and against the action of the spring 18 to release the fastening means, upon shifting the bar 23 to the left, in the drawings. The lip 29 on the bar 23 is so positioned that it is spaced from the wall of the door-opening, when the device is in normal position, Fig. 1, a distance sufficient to insure the disengagement of the catch 15 from the keeper before force is applied through the bar 23 to force the door open.

It will be readily understood from the foregoing that my improved device is simple and economical of construction, will operate positively, and does not present any objectionable obstructions especially to those working about the cars in the loading and unloading of the latter.

While I have illustrated and described a particular embodiment of my invention, I do not wish to be understood as intending to limit it thereto, as the same may be variously modified and altered without departing from the spirit of my invention.

What I claim as new and desire to secure by Letters Patent is:

1. The combination with members rela-

tively movable toward and away from each other, of means for forcing said members apart comprising a shiftable device supported on the outer face of one of said members to move toward and away from the other of said members and carrying a rearwardly-extending lug movable therewith, one of said members containing a recess in its edge-portion opposing the other of said members, and opening through the outer face of the member and extending rearwardly of the outer face of the other member and into which recess said lug projects, said shiftable device being adapted to engage at its lug the edge portion of one of said members other than the one carrying it and force said members apart when actuated.

2. The combination with members relatively movable toward and away from each other, of means for forcing said members apart comprising a shiftable device supported on the outer face of one of said members to move toward and away from the other of said members and carrying a rearwardly-extending lug movable therewith, one of said members containing a recess in its edge-portion opposing the other of said members, and opening through the outer face of the member and extending rearwardly of the outer face of the other member and into which recess said lug projects, said shiftable device being adapted to engage at its lug the edge-portion of one of said members other than the one carrying it and force said members apart when actuated, and a lever pivoted on the member carrying said shiftable member and connected with the latter for operating it.

MATTHEW J. FLANNERY.

In presence of—

HENRY HEINER,
H. L. SCHOLONG.
